UNITED STATES PATENT OFFICE.

WILLIAM C. HUSS, OF CINCINNATI, OHIO.

DESIGN FOR A WALL-FIXTURE FOR COUNTERS.

SPECIFICATION forming part of Design No. 21,907, dated October 18, 1892.

Application filed September 21, 1892. Serial No. 446,477. Term of patent 3½ years.

To all whom it may concern:

Be it known that I, WILLIAM C. HUSS, a citizen of the United States, and a resident of Cincinnati, in the county of Hamilton and State of Ohio, have invented certain new and useful Improvements in Designs for Wall-Fixtures for Counters, of which the following is a specification.

My invention is a new and original design for a wall-fixture for a counter, the leading features of which are the entablature, the columns supporting it, and the ornamentation on the frieze and architrave, as shown in the accompanying drawings, in which—

15 Figure 1 is a front view of one-half of a fixture made according to my design. Fig. 2 is an end view of the same.

The sideboard or closet part A of the fixture is recessed back of the pedestals A'. A 20 projecting top a covers the pedestals and closets. The closets are fitted with paneled doors a' and above the doors with paneled drawer-fronts framed with carved moldings. Upon the pedestals A' at each end of the 25 fixture rest two circular columns B, which are surmounted by carved capitals B'. The capitals are nearly rectangular, the corners only being rounded slightly and with the sides turned in abruptly to meet the necks 30 of the columns, which are beaded and are below the beaded portion ornamented with scrollwork. The upper parts of the capitals conform nearly to the rectangular abacus which surmounts them. The shafts of the 35 columns are preferably of lighter-colored material than the body of the fixture and highly polished. Immediately back of the columns, upon each side, is a mirror-plate c, which reflects the columns and gives the appearance 40 of four instead of two columns at each end to support the entablature.

The architrave C above the columns has sunken carved panels. The architrave has a 45 projecting corbel C', apparently supporting the upper facia, which, like the corbel, projects forward in a bold curve. The portion

of the corbel below the facia is carved scroll-work. In a panel formed by the facia and curved molding beneath carved spandrels c' complete the central ornamentation upon 50 each side of the corbel. The architrave between the carved end panels and the corbel is ornamented by carved shields c² and ribbon c³. Below the lower facia of the architrave and above the sideboard is a molded 55 frame inclosing a mirror D.

The cornice E is supported by two rectangular pilasters F at each end, from the center portions of which project triple brackets, which terminate in jets or globes. In the 60 space between the pilasters, at each end, is a sunken panel, in which is the figure of a female and foliage in bas-relief. The ends and center of the cornice project forward, and the center portion is apparently supported by 65 four columns upon each side. The columns have carved capitals and a common abacus for all of them.

The center-piece of the frieze is an arch, which partially conceals the lower parts of the 70 two inner columns upon each side.

The arch surrounds a reflecting-panel G, in front of which is arranged an ornamental torch, the bowl of which is open fretwork, within which is a globe g.

The background of the frieze between the 75 pilasters and center-piece is formed in imitation of lattice-work, and preferably of stucco or carton pierre colored darker than the material of the fixture. Upon the frieze between 80 the pilasters and center-piece, upon each side, are three patera in bas-relief. In the center of each patera is an ornamental shield in alto-relief.

What I claim is—

The design for a wall-fixture for counters, substantially as herein shown and described.

WILLIAM C. HUSS.
